UNITED STATES PATENT OFFICE.

LEE U. HAWKINS, OF MADISONVILLE, KENTUCKY.

NAME STAMP FOR CONCRETE WORK.

Application filed March 25, 1922. Serial No. 546,706.

To all whom it may concern:

Be it known that I, LEE U. HAWKINS, a citizen of the United States, residing at Madisonville, in the county of Hopkins and 5 State of Kentucky, have invented certain new and useful Improvements in Name Stamps for Concrete Work, of which the following is a specification, reference being had to the accompanying drawings.

10 This invention relates to stamps, and particularly to stamps designed to be used with plastic materials and prior to the final hardening of the plastic material, the object of the invention being to provide a stamp 15 which, when pressed against the plastic mass, will impress the plastic mass with raised letters.

A further object is to provide a device of this character in which the letters are perforated so as to permit the escape of air and thus cause the plastic mass to enter into the recesses forming the letters in the stamp.

Still another object is to provide a stamp of this character with removable and inter- 25 changeable letters.

Other objects will appear in the course of the following description.

My invention is illustrated in the accompanying drawings, wherein:—

30 Figure 1 is an edge elevation of one form of my hand stamp;

Figure 2 is a longitudinal sectional view thereof;

Figure 3 is a top plan view of another 35 form of stamp;

Figure 4 is an under side plan view thereof;

Figure 5 is a fragmentary sectional view 40 showing the manner in which the printing blocks or pieces are held in place;

Referring to Figure 1, 10 designates a stamp which may be made of wood, metal, or any other suitable material, and which is in one solid piece and which may have any 45 suitable form, as for instance the form of a diamond, square, circle, or the like. I have illustrated a stamp having the form of a diamond, but obviously I do not wish to be limited to this.

50 This stamp upon its outside face carries a handle 11. The inside face of the stamp is formed with depressed letters, that is recesses 12 having the form of letters or having an ornamental form, these letters being 55 sunken into the face of the stamp, and each letter, figure or ornament having extending

from it a plurality of perforations 13 opening upon the outer face of the stamp. These perforations 13 are particularly vital, inasmuch as they permit the escape of air. If 60 no perforations were present, the stamp would not work properly and would not give a clearly defined raised letter on the work, for the reason that the air would be trapped in the recesses, could not escape, and would 65 prevent the filling of the recesses with the plastic mass.

In Figure 3, I show another form of my invention particularly designed for use in pressing concrete blocks, curbstones, flagstones, or the like with the names of streets or the names of persons or places. In this drawing is shown a frame consisting of a plurality of parallel bars 14 connected at the ends and intermediate the ends by transverse bars 15. The bars 14 are disposed inside of the bars 15 and these bars 14 are formed to provide longitudinally extending grooves 16. Inasmuch as there are three bars 14, the middle bar 14^a having double 70 grooves 16, it follows that there are two slideways and in these slideways letter blocks 17 are designed to fit having laterally projecting flanges 18 engageable in the grooves 16. The face of each block 17 is 75 formed with a sunken letter, figure or ornament, as heretofore described, and designated 19, and these sunken or depressed lines forming the letters, figures or ornaments are connected to the front of the block 80 or outside face of the block by means of the perforations 20. A handle 21 is attached to the outside face of the frame.

With this construction it is obvious that the letter blocks or figure blocks or blocks 95 having sunken ornaments on their faces may be inserted in the guideways between the bars 14 and 14^a so as to give the name of a place or person and then this mold or stamp may be used for forming raised characters 100 upon the face of the plastic mass prior to its eventual hardening. This invention makes raised letters or figures upon the face of the concrete or other plastic mass which may be used to advertise the builders of flat work, 105 such as floors, sidewalks, curbs, gutters, retaining walls, bridges, etc. The last letter stamp is intended to be used in numbering streets or stamping the names of individual property owners or the number of the house 110 on work done in front of their respective homes.

The form of stamp illustrated in Figure 1 can be made in sheet metal. It makes it light and attractive. The stamp is used after the surface of the work has been 5 troweled and the water has evaporated. The stamp is laid on the concrete and tapped lightly and the desired result is secured. Obviously I do not wish to be limited to the exact form of the stamp illustrated, as this 10 might be varied in many ways without departing from the spirit of the invention as defined in the accompanying claims.

I claim:

1. A stamp for plastic material having a 15 face having indentations defining characters, the indentations communicating with the back of the stamp and the atmosphere by perforations and a handle forming part of the stamp and disposed on the opposite face 20 of the stamp from said indentations.
2. A stamp of the character described comprising a frame having a handle, and a plurality of interchangeable blocks insertable into the frame, each of said blocks having a face formed with an indentation defining a character, the indentation communicating with the back of the block and the atmosphere by a perforation.
3. A stamp of the character described 30 comprising a frame including a plurality of

parallel bars, these bars having confronting recesses formed on their edge faces, the frame having a handle, and interchangeable blocks insertable into place between said bars and having flanges engaging the recesses, 35 each of said blocks having upon its faces an indented character, the character having a perforation communicating with the opposite face of the block and with the atmosphere.

4. A stamp of the character described comprising a frame including a plurality of parallel bars defining longitudinally extending spaces, the margins of said bars bordering said spaces being bent outward from the faces 45 of the bars to form longitudinally extending slots, and interchangeable members adapted to be disposed between said bars, each of said members being formed of sheet metal and having inwardly bent margins formed with 50 laterally extending flanges adapted to be inserted in said slots and each of said members having an indented character upon its face, each character having perforations communicating with the inner face of the 55 member and with the atmosphere.

In testimony whereof I hereunto affix my signature.

LEE U. HAWKINS.
